FLUIDIZED COKING

Theodore H. Schultz, Munster, Ind., assignor to Sinclair Refining Company, New York, N. Y., a corporation of Maine

Application December 4, 1951, Serial No. 259,854

1 Claim. (Cl. 202—15)

My invention relates to improvements in the art of coking hydrocarbon oils, such as those derived from crude petroleum to convert them into distillate stocks and a minimum of residue in the form of coke. Application Serial No. 121,575, filed October 15, 1949, of Kenneth M. Watson, now Patent No. 2,707,702, deals with coking operations in which a body of coke particles is maintained in a fluidized state in a reaction vessel, in which hydrocarbon oil is introduced into the fluidized body of coke particles in the reaction vessel, in which a coking temperature is maintained in the reaction vessel, in which vapors are taken off overhead from the reaction vessel, and in which large coke particles are selectively removed as formed from the fluidized body of coke particles by elutriation to maintain equilibrium. In these coking operations, the hydrocarbon oil charge stock is preheated to about 800° to 975° F. depending upon the nature of the stock and heater limitations, before injection into the coke bed. The discharge temperature from the heater coil must be limited to about 925° to 975° F. due to the increasing rate of formation of coke and coking materials in heavy oil charge stocks at high temperature. Since the economics of the coking process require relatively high temperatures in the reaction vessel, e. g. 950° to 1100° F., for good rates of reduction of residual charge stock and maximum production of distillate stock, and since the coking reaction is an endothermic reaction, heat from an extraneous source must be supplied to the reaction vessel. The heat advantageously is supplied by employing superheated steam as a fluidizing medium and dispersion medium for the heavy oil charge but at the higher coking levels, the volume of steam required may become uneconomical. Heated hydrocarbon stocks such as the effluent from thermal cracking or reforming units may be utilized as heat carriers but this increases the size of equipment required and imposes additional burdens on the fractionating equipment. Also where the primary purpose of the coking operation is to produce charge stocks for catalytic cracking, it is undesirable to admix cracked distillates with the coker gas oil.

In the coking process of my invention the heavy oil charge stock is coked in the presence of a body of coke particles maintained in a fluidized state at high coking temperature, and a substantial portion of the heat for the coking reaction is supplied by a hot olefin rich gaseous hydrocarbon stream.

According to my invention, a stream of gaseous hydrocarbons is separately preheated to an elevated cracking temperature for a restricted period of time to provide an olefin rich gas stream which is introduced into a coking reactor at a flow rate and in sufficient amount to maintain a high coking temperature in the coking reactor in which the coking stock is contacted with a body of coke particles maintained in a fluidized state. Large coke particles are selectively withdrawn from the fluidized bed by elutriation and a vapor mixture is taken off overhead from the coking reactor. Advantageously, the olefin rich gas stream is employed as the fluidizing medium. With par-

2

ticular advantage, the gaseous hydrocarbons comprise hydrocarbon gases other than methane, e. g. ethane to butane, and are subjected to rapid pyrolysis to produce a gas stream of maximum olefin content and minimum aromatic content. Within the coking reactor, time is provided for polymerization of olefins to aromatics by passage of the olefin rich stream through the coke bed, which aromatics are recoverable from the condensed coking reaction products.

- 10 The pyrolysis of gaseous hydrocarbons to produce aromatics takes place thermodynamically in two stages after the gaseous hydrocarbons are heated to a cracking temperature. A rapid primary decomposition takes place with absorption of heat which is followed by slower 15 aromatic forming reactions with evolution of heat. For example, when butane is heated at a cracking temperature under 2 atmospheres pressure for 0.15 second, the exothermic heat developed between 0.15 and 4.8 seconds is about 340 B. t. u. per pound.
- 20 In the process of my invention the gaseous hydrocarbons are cracked in a separate cracking zone where heat is absorbed to the limit of a theoretical maximum heat content corresponding to the formation of the maximum 25 concentration of gaseous olefins at which point they are injected into the coking reactor to provide sufficient soaking time for the exothermic aromatics forming reaction. Thus the need for employing large amounts of heated hydrocarbon vapors or excessive quantities of high temperature steam is avoided by utilizing the exothermic heat 30 of polymerization of olefins to aromatics to fulfill the requirement for extraneous heat which must be supplied to the coking reactor.

The stream of gaseous hydrocarbons is preheated to an elevated cracking temperature of about 1100° to 1600° F. under pressures of about 10 to 250 p. s. i. g. for a restricted period of time of less than about 0.2 second, preferably about 0.08 to 0.1 second. The resulting olefin rich gas stream is introduced into the coking reactor at a flow rate and in sufficient proportion to the quantity of 40 coking charge stock to maintain a coking temperature of about 950° to 1100° F. Temperature control in the coking reactor may be effected in several ways, alone or in combination. For example, the proportions of olefin rich gas and coking feed may be varied, or the residence time of the hydrocarbon gases in the heater and their 45 soaking time in the coking reactor may be regulated to vary respectively the amount of superheat and heat of polymerization given up by the hydrocarbon gases. In addition, the soaking time of the olefin rich gas stream in the coking reactor may be regulated to produce the maximum amount of benzene or a larger amount of tar with a corresponding increase in exothermic heat. Also the temperature at which the coking charge stock enters 50 the coking reactor may be varied, as may be the level in the fluidized coke bed at which the olefin rich gas stream is introduced. Or another gas such as steam may be employed to furnish all or a part of the fluidizing gas requirement. Thus temperature control may be readily adjusted after start up with, for example, superheated steam as the fluidizing medium.

- 60 Conventional gas cracking operations present the problem of efficient recovery of the high heat content of the cracked gases. Handling and separation of the product mixture presents additional difficulties including disposal of by-product tars and carbon. My invention has definite 65 economic advantages with respect to heat and product recovery in gas cracking operations. For example, the excess heat including the heat of polymerization of the olefins in the gas stream to aromatics is recovered in the coking reactor and the heat content of the vapor effluent from the coking reactor may be used to preheat the coking charge stock or to generate steam for use as a fluidizing

or elutriating medium. The carbon and tars produced in the gas cracking operation are collected in the coking reactor or reduced to coke in the coking reactor by recycle of heavy ends from the fractionating column. The desirable aromatics may be removed from the liquid coking reaction products by fractionation. For example, the vapor effluent may be fractionated to obtain a fraction containing mostly benzene which may be recovered therefrom as by extractive distillation with a selective solvent for aromatics. Valuable gases such as propylene and butylene also may be recovered from the fractionating units.

By way of further illustration, I will describe my improved coking process as carried out in the equipment illustrated in the accompanying drawing.

The illustrated apparatus comprises a reaction vessel 10, separate heaters 11 and 12 and fractionating columns 14 and 15. Heater 11 may be a fired heater of any conventional construction embodying one or more series of connected tubes, the deFlorez heater for example or it may be a conventional preheater of the heat exchange type. Heater 12 may be a conventional cracking heater containing a high temperature resistant tube coil of, for example, chromium-alloy steel or carborundum. Conical grid 17 opening into the upper end of elutriator 18 is spaced just above the lower end of reaction vessel 10. Reaction vessel 10 is with advantage relatively high with respect to its diameter, as illustrated. An olefin rich hydrocarbon gas stream for fluidizing the body of coke particles maintained in the reaction vessel above grid 17 is discharged from cracking heater 12 through connection 19 into the space below the grid and passes upwardly through the grid into the body of coke particles. A hydrocarbon gas stream is introduced into cracking heater 12 by means of line 20. Elutriating steam, superheated, is introduced into the lower part of elutriator 18 through connection 21. The lower end of elutriator 18 opens into coke hopper 22 from which coke is discharged through connection 23. Residual charge stock is introduced into reaction vessel 10 through heater 11 and connection 24. The overhead from reaction vessel 10 passes to the lower part of fractionating column 14 through connection 25. Pressures of 10 to 80 p. s. i. g., for example, may be maintained in the fractionating columns. Higher pressures maintained in the reaction vessel are reduced by means of valve 26 located at the discharge end of connection 25. Pressure in heater 11 may be regulated and reduced to reaction vessel pressure, if higher pressure is maintained in heater 11, by means of valve 27 in connection 24. Pressure in cracking heater 12 may be regulated and reduced to reaction vessel pressure, if higher pressure is maintained in the heater, by means of valve 28 in connection 19. The relatively high boiling distillate fraction derived from the residual stock supplied through connection 29 by the coking in reaction vessel 10 is recovered as high boiling stock discharged as a sidestream from fractionating column 14 through connection 30 and as a bottom stream from the lower end of fractionating column 14 through connection 31. If any significant amount of coke fines is carried over into column 14 from reaction vessel 10, the heavy stock discharged from the lower end of column 14 containing such fines may be reintroduced into reaction vessel 10 through heater 11. Noncondensable gas is withdrawn from fractionating column 14 by means of line 32. A hydrocarbon fraction boiling in the range of about 130° to 250° F. containing gasoline or naphtha and aromatics is withdrawn from column 14 as a sidestream through connection 33 and introduced into the lower part of fractionating column 15. A heavy naphtha fraction is withdrawn from column 15 by means of line 34.

The overhead from fractionating column 15 containing the products of the coking operation and the aromatics of the polymerization reaction boiling in the range of about

150° to 185° F. pass through connection 16 to appropriate solvent extraction and recovery equipment not shown.

In carrying out the process of my invention in the apparatus illustrated, operation is initiated by charging reaction vessel 10 with coke particles, for example, from a previous run or ground to pass a screen of from 6 to 10 mesh per inch. This charge of coke particles may be, for example, about 9 feet in diameter and 22 feet high. The superficial velocity through the coke charge may approximate from 1½ to 5 feet per second. A straight-run residual stock, for example, a reduced crude is heated to a temperature short of that at which coke deposition in the heater begins within the time factor in the heater, 800° to 975° F., usually not above about 920° F., under a discharge pressure of 10 to 250 p. s. i. g., in heater 11. A stream of hydrocarbon gas other than methane, and advantageously containing olefins is heated to a high cracking temperature, 1100° to 1600° F., under a pressure of 10 to 250 p. s. i. g., during an exposure time of about 0.1 second in heater 12. The time factor in reaction vessel 10 approximates 10 to 50 seconds. The coking temperature is maintained in the reaction vessel without heating the residual stock to a temperature exceeding about 975° F., or that at which coke deposition within the heater begins, by means of the superheat of the olefin rich gaseous hydrocarbon effluent from high temperature cracking heater 12 and by means of the exothermic heat of polymerization of the olefins to form aromatics. Good heat economy is effected by this utilization of the superheat and the heat of polymerization of the olefin rich gas stream to supply the substantial heat required for coking the residual stocks and to maintain a high reaction temperature in the reaction vessel. Coke building material derived from the residual stocks, and the small amount of such material produced by the cracking of the gaseous hydrocarbon, deposits on the coke particles, which as a result, grow as deposited material is coked. As the coke particles grow, larger particles are selectively discharged through elutriator 18 and connection 23, the admission of elutriating steam, superheated, through connection 21 being regulated with respect to discharge of coke pellets to maintain a substantially constant volume of growing coke particles in reaction vessel 10. The vapor mixture taken overhead from fractionating column 15 is a fraction boiling within the range of about 150° to 185° F. This fraction is conventionally treated to remove aromatics therefrom as by extractive distillation with a selective solvent for aromatics such as liquid sulfur dioxide.

I claim:

50 In a method for coking hydrocarbon oils by contacting the coking stock at a high coking temperature with a body of coke particles maintained in a fluidized state in a coking reactor from which large coke particles are selectively withdrawn by elutriation, the improvement which 55 comprises separately preheating a stream of normally gaseous hydrocarbons to an elevated cracking temperature of about 1100° to 1600° F. under pressures of about 10 to 250 p. s. i. g. for a restricted period of time of less than about 0.2 second to provide an olefin rich gas stream, 60 introducing into the coking reactor the olefin rich gas stream at a flow rate and in sufficient amount to maintain by means of its sensible heat and its exothermic heat of polymerization a high coking temperature in the coking reactor, and withdrawing an overhead stream from the 65 coking reactor.
